ICE TRAY

Lloyd M. Keighley, Dayton, Ohio, assignor to
General Motors Corporation, Dayton, Ohio, a
corporation of Delaware

Application April 8, 1938, Serial No. 200,955

9 Claims. (Cl. 62—108.5)

This invention relates to freezing devices for refrigerating apparatuses and particularly to a device for freezing liquids into ice blocks.

I am aware of the fact that others have provided liquid freezing devices including a tray and a grid therefor which divides the interior of the tray into a plurality of ice compartments and wherein the grid is of rigid metal wall construction with all the walls thereof vertically disposed and normally positioned at an angle to one another to provide parallelogram-shaped ice block compartments. In such structures the grid walls are movable out of their normal angled position to break ice blocks loose therefrom and to enlarge the compartments to liberate the ice blocks from the grid. Some difficulty has been encountered in providing a freezing device of the type described with a suitable mechanism for separating the grid from the tray and for moving the grid walls relative to one another. For example, in prior freezing devices wherein all the grid walls are vertically positioned and disposed at an acute angle relative to one another, a mechanism including an operating lever has been provided for moving the grid walls out of their normal acute angled position into substantially right-angled positions relative to one another. In this prior freezing device the operating lever has been arranged for movement in one direction to separate the grid structure and ice blocks adhering thereto from the tray and for movement in another direction to move the walls of the grid structure for releasing ice blocks therefrom. These different motions of the operating lever are confusing to the user and, quite frequently, application of too much force upon the lever in the wrong direction has resulted in damaging or breaking the mechanism associated therewith. I, therefore, contemplate the provision of an improved freezing device of the type described which will overcome the difficulty explained and which can be manipulated without confusion to thereby facilitate the act of harvesting ice blocks therefrom.

One object of my invention is to provide an improved rigid movable grid wall structure adapted to be disposed in an ice tray for dividing the tray into a plurality of ice block compartments and a novel method of removing the grid from the tray and ice blocks from the grid structure.

Another object of my invention is to provide an ice tray with a removable rigid metal walled unitary grid structure which structure has all its walls disposed in a vertical position and includes a longitudinal wall and a set of spaced apart walls extending laterally from each side thereof with the walls of one lateral set extending in a different acute angled direction relative to the walls of the other lateral set to form rows of ice block compartments of parallelogram shape and

in which structure the lateral walls are movable out of their angled extension to break ice blocks loose from the walls and to enlarge the compartments to release ice blocks therefrom.

A further object of my invention is to employ a means having a single direction of motion for moving certain of the walls of a grid structure of the type described in the preceding object relative to other walls thereof for also elevating the grid and ice blocks bonded thereto relative to the tray.

A still further and more specific object of my invention is to provide a grid structure of the type described in the preceding objects wherein the laterally extending angled walls are hinged to the longitudinal wall and have their outer extremities secured in spaced apart relation to one another and wherein they are moved out of their acute angled extension relative to the longitudinal wall by movement of the longitudinal wall lengthwise of the grid structure or by movement of all the angled walls of the sets thereof relative to the longitudinal wall and toward one end of the grid structure.

Further objects and advantages of the invention reside in details of construction and in novel combinations and arrangements of parts thereof as will more fully appear in the course of the following description.

In the drawings:

Fig. 1 is a top plan view of a freezing device including a tray and a grid constructed in accordance with the present invention disposed in the tray;

Fig. 2 is a side view of the device disclosed in Fig. 1 showing the tray in section;

Fig. 3 is a vertical transverse sectional view through the freezing device taken on the line 3—3 of Fig. 2;

Fig. 4 is a view similar to Fig. 2 showing the grid and ice blocks bonded thereto elevated relative to the tray;

Fig. 5 is a plan view of the grid removed from the tray and disclosing certain walls of the grid moved relative to other walls thereof to illustrate the manner in which ice blocks are released from the grid;

Fig. 6 is a side view of the grid with ice blocks released therefrom to illustrate the movement of the lateral grid walls into a right-angled position relative to the longitudinal grid wall;

Fig. 7 is a fragmentary enlarged view of a portion of the grid showing the association of the lever with the longitudinal grid wall;

Fig. 8 is an enlarged fragmentary top view showing a hinged connection of the lateral walls with the longitudinal wall of the grid structure;

Fig. 9 is a side view of the hinged connection of the grid walls and is taken in the direction of the arrow 9 in Fig. 8; and

Fig. 10 is a view showing the connection of an actuating bar with the lateral grid walls.

Referring to the drawing, for illustrating my invention, I have shown my improved liquid freezing device as including a metal ice tray 11 having side walls 12 (see Fig. 3), a bottom wall 13 and opposed end walls 14 and 15. The upright walls of tray 11 diverge outwardly toward the top of the tray to facilitate removal of a grid, generally represented by the reference character 16, disposed in the tray. The walls 12, 14 and 15 of tray 11 have their upper portion rolled over as at 17 to provide a rim which extends continuously around the top of the tray to increase its structural strength. A portion of the metal of tray 11 is extended downwardly from rim 17, as at 18 (see Fig. 2), at the front of the tray and provides a mounting for a heavy metal piece 19 which has a handle 20 pivotally secured thereto as at 21. The handle 20 facilitates placing of the freezing device in or on a freezing support or shelf of an evaporator of a refrigerating system and a cam surface 22 formed thereon functions, upon actuating the handle, to break on ice bond between the tray and its support to permit removal of the freezing device and its frozen contents from the evaporator in the well-known manner.

The grid 16 disposed within tray 11 is of a unitary metallic construction and is removable from the tray. This grid structure 16 includes a substantially non-flexible or rigid longitudinal metal wall 25 and a plurality of substantially non-flexible or rigid metal walls 26 extending laterally therefrom in spaced apart relation along the length thereof to divide the interior of tray 11 into longitudinal rows of ice block compartments 28. The plurality of metal walls 26 are arranged in two sets, one of which is located on one side of longitudinal upright wall 25 and one of which is located on the opposite side of wall 25. It is to be noted that walls 26 are vertically disposed and are arranged parallel to one another and that these walls of one set thereof extend laterally in one direction at an acute angle relative to longitudinal wall 25 while the walls 26 of the other set thereof extend laterally in another direction at an acute angle relative to wall 25. The acute angled disposition or arrangement of the vertical walls 26 normally provides the ice block compartments 28 with a parallelogram form (see Fig. 1) and are movable out of their normal angled extension into a substantially right-angled position relative to longitudinal wall 25 to enlarge the ice block compartments in a manner to be hereinafter more fully described. Walls 26 are each separate from and independent of one another and are hinged to longitudinal wall 25 for movement relative thereto. The upright or vertical longitudinal wall 25 is provided with a plurality of spaced apart cut-out slots 31 extending downwardly from its top edge (see Figs. 8 and 9) and with a plurality of spaced apart slots 32 extending upwardly from its bottom edge. Wall 25 is also provided with a plurality of horizontal slits 33 (see Fig. 9), and the metal intermediate these slits 33 is formed outwardly of one side of the wall 25 as at 34 (see Fig. 8). The metal of wall 25 located between slits 33 and the inner wall of slots 31 and 32 is formed outwardly of the opposite side of the longitudinal wall as at 36 (see Fig. 8). The deformation of wall 25 as described provides a vertical opening the walls of which are formed by the bent web portions 34 and 36. Each lateral wall 26 of the set thereof on one side of longitudinal wall 25 is provided

with a pair of looped portions 37 (see Fig. 9), the openings of which register with the opening formed by the webs 34 and 36 of wall 25. Each lateral wall 26 of the set thereof on the opposite side of longitudinal wall 25 is provided with a pair of looped portions 38 (see Fig. 9), the openings of which also register with the opening formed by webs 34 and 36 of the wall 25. A pin or shaft 39 having a relatively flat head portion 41 is extended through the openings of looped portions 37 and 38 of walls 26 and through the opening formed by the webs 34 and 36 of wall 25 to hingedly mount the laterally projecting walls 26 upon the longitudinal grid wall 25. The upper end 42 of pins or shafts 39 may be beaded over for locking the walls together to provide a unitary structure. In order to hold the walls 26 in parallel spaced apart relation to one another, I secure a bar 44 to the outer extremity of each set of walls. It will be noted that each wall 26 has an integral rounded portion 45 (see Fig. 10) extending upwardly from its top edge adjacent its outer side edge. The two bars 44 are each provided with a plurality of spaced apart openings 46 which loosely receive the rounded extensions 45 on wall members 26. After the bars 44 are assembled to members 26 the end of portions or extensions 45 are beaded over as at 47 to lock the two bars to the grid.

To complete the unitary grid structure 16 and to provide means for actuating the bars 44 and, consequently, moving the lateral grid walls 26, I pivotally mount a lever 51, having a handle end 52, to the longitudinal grid wall 25 as by a pin 53 passing through an opening 54, in wall 25, and through suitable openings provided in a pair of legs 55 formed on and depending from the lever (see Fig. 7). The lever 51 is provided with a pair of ears 56 which extend outwardly from a yoke portion 57 thereof and over the rim 17 at the back wall 14 of the ice tray 11. Legs 55 on lever 51 straddle the longitudinal grid wall 25 and the underside of yoke 57 of lever 51 is cut away as at 58 to permit elevation of the lever without striking the grid wall 25. It is to be noted that the opening 54, provided in grid wall 25 and through which pin 53 extends, is of an elongated form for a purpose to be hereinafter more fully explained. The rounded pivot portion 59 extends outwardly from each side of the yoke 57 of lever 51 and is received in an opening 61 provided in a twisted end portion 62 of the bars 44 (see Figs. 1 and 7). The lever 51 is thereby secured to the grid structure 16 for movement in a single direction of motion about its pivotal mountings 59. Since lever 51 moves in a single direction about the pivot points 59, it is obvious that opening 54 in the longitudinal grid wall 25 must be elongated to permit such movement.

It is apparent that the connection of lever 51 with bars 44 normally maintains the vertically disposed laterally projecting sets of grid walls 26 in a position whereby they extend in different acute angled directions relative to one another and to the longitudinal grid wall 25 to provide the ice block compartments with a parallelogram form. The hinged or pivotal mounting of walls 26 permits movement thereof out of their normal acute angled projection into substantially a right-angled or perpendicular position relative to the longitudinal grid wall 25 to change the form or contour of compartments 28. Movement of the walls 26, after the grid structure 16 has been removed from tray 11, breaks ice blocks loose from the grid walls and the changing of the contour

of the ice block compartments enlarges these compartments and permits the loosening ice blocks to freely fall therefrom. Since force is applied to the outer extremity of the laterally projecting walls 26 through the bars 44, a minimum of pressure exerted upon the operating lever 51 will move the walls.

Assume that water has been frozen in the tray 11 of the freezing device in the form of ice blocks 10 in compartments 28, by the refrigerating effect produced by an evaporator of a refrigerating system, and tray 11 has been removed from the evaporator by manipulating the handle 20 and it is now desired to harvest the ice blocks from the device. The handle end 52 of lever 51 is elevated to cause the ears 56 thereon to engage rim 17 at the back of tray 11 and apply force thereto. During this elevating movement of lever 51 about its pivotal mountings 59, pin 53 secured to legs 55 of the lever moves freely within the elongated opening 54 in grid wall 25. Pin 53 moves along and in engagement with the top wall of opening 54 in grid wall 25, and when the ears 56 on lever 51 engage the element 17 of tray 11 to apply force to the tray this force is transmitted to the longitudinal wall 25 of the grid structure 16 through pin 53. Thus, the elongation of opening 54 in grid wall 25 permits this initial movement of lever 51. The force applied to tray 11 by lever 51 and transmitted to the grid 16 in the manner described causes the unitary grid structure together with ice blocks adhering or bonded thereto to be elevated relative to the tray as shown in Fig. 4 of the drawings. Breaking of the bond between the ice and walls of tray 11 as shown in Fig. 4 permits the grid structure 16 and ice blocks therein to be removed from the tray. After the grid and ice have been removed from the tray the handle end 52 of lever 51 is moved further in its 40 single direction of motion about the pivots 59 as shown in Figs. 5 and 6 of the drawings. This further or continued movement of lever 51 actuates bars 44 toward the lever end of the grid structure, and the lengthwise movement of the 45 bars 44 also moves the outer portions of the laterally extending grid walls 26 toward the lever end of the grid (see Figs. 5 and 6). The grid walls 26 pivot about the hinged pins 39 and when moved into a substantially right-angled position 50 relative to grid wall 25 the ice block compartments 28 are enlarged as may be determined by reference to Fig. 5 of the drawings. During movement of walls 26 the bond between the ice blocks and the grid walls 25 and 26 is broken to loosen 55 the ice blocks and permit them to fall freely from their compartments when these compartments are enlarged. The enlargement of the ice block compartments is caused by changing their shape or contour from a parallelogram to substantially a rectangular form. I have shown the ice blocks 60 still in their respective compartments in Fig. 5 of the drawings to illustrate the enlargement of the compartments relative to the size of the ice blocks, but it is to be understood that when the grid walls 65 are moved, as described, these ice blocks will be loosened and will fall freely out of their compartments. After the ice blocks have been removed from the grid structure 16, the lever 51 may be moved back into its normal position and this 70 return movement of lever 51 moves the laterally extending vertical grid walls 26 back into their normal acute-angled position relative to the upright longitudinal grid wall 25 to form the parallelogram-shaped ice compartments 28. If desired, the tray and grid walls may be treated or

coated with a waxy substance to decrease the adhesions of ice thereto so as to facilitate removal of ice blocks therefrom.

From the foregoing it will be apparent that I have provided a vertically disposed grid wall structure in which the walls are arranged to form parallelogram-shaped ice block compartments and in which certain walls are movable relative to other walls thereof to enlarge the ice block compartments. In this improved vertically disposed grid wall structure, a lever having a single direction of motion is employed to elevate the grid and ice bonded thereto relative to the tray and to also move the grid walls to release ice blocks therefrom. By constructing the grid of metal walls I have retained the fast freezing characteristics of metal grid and tray combinations. In the improved structure disclosed, force is applied to the outer extremity of the movable grid walls and less effort on the part of the operator is thereby required to move the grid walls to thus facilitate the operation of harvesting ice blocks from a freezing device.

While the form of embodiment of the invention as herein disclosed, constitutes a preferred form, it is to be understood that other forms might be adopted, all coming within the scope of the claims which follow.

What is claimed is as follows:

1. A grid for disposition in an ice tray comprising, a rigid longitudinal upright wall having two sets of rigid vertically disposed walls projecting laterally from the sides thereof to provide longitudinal rows of ice block compartments, the vertically disposed walls of one set of said laterally projecting walls being parallel to one another and extending in one direction transverse of the grid at an acute angle relative to said longitudinal wall, the vertically disposed walls of the other set of said laterally projecting walls being parallel to one another and extending in another direction transverse of the grid at an acute angle relative to said longitudinal wall, the normal acute angled disposition of said laterally projecting walls providing said ice block compartments with a parallelogram form, said vertically disposed laterally projecting walls of each set thereof being movable toward the same end of the grid out of their normal acute angled extension towards a right angled position relative to said upright longitudinal wall to break ice blocks loose from said grid walls and to enlarge said ice block compartments, and means for imparting force to said laterally projecting vertical walls to cause said movement thereof.

2. A grid for disposition in an ice tray comprising, a rigid longitudinal upright wall having two sets of rigid vertically disposed walls projecting laterally from the sides thereof to provide longitudinal rows of ice block compartments, the vertically disposed walls of one set of said laterally projecting walls being parallel to one another and extending in one direction transverse of the grid at an acute angle relative to said longitudinal wall, the vertically disposed walls of the other set of said laterally projecting walls being parallel to one another and extending in another direction transverse of the grid at an acute angle relative to said longitudinal wall, the normal acute angled disposition of said laterally projecting walls providing said ice block compartments with a parallelogram form, said vertically disposed laterally projecting walls of each set thereof being movable toward the same end of the grid out of their normal acute angled

- extension towards a right angled position relative to said upright longitudinal wall to break ice blocks loose from said grid walls and to enlarge said ice block compartments, and means
- 5 engaging each of said laterally projecting vertical walls at a point remote from said longitudinal wall and near their lateral extremity for imparting a force thereto to cause said movement thereof.
- 10 3. A grid for disposition in an ice tray comprising, a rigid longitudinal upright wall having two sets of rigid vertically disposed walls projecting laterally from the sides thereof to provide longitudinal rows of ice block compartments, the vertically disposed walls of one set of said laterally projecting walls being parallel to one another and extending in one direction transverse of the grid at an acute angle relative to said longitudinal wall, the vertically disposed
- 15 walls of the other set of said laterally projecting walls being parallel to one another and extending in another direction transverse of the grid at an acute angle relative to said longitudinal wall, the normal acute angled disposition of said laterally
- 20 projecting walls providing said ice block compartments with a parallelogram form, said vertically disposed lateral walls of each set thereof being pivotally hinged to said upright longitudinal wall for movement toward the same end of the grid out of their normal angled extension
- 25 towards a right angled position relative to said longitudinal wall to break ice blocks loose from said walls and to enlarge said ice block compartments, means engaging each of said laterally projecting vertical walls at a point remote from said longitudinal wall and near their lateral extremity for causing said movement thereof, and a single lever for imparting force to said means.
4. A grid for disposition in an ice tray comprising, a rigid longitudinal upright wall having two sets of rigid vertically disposed walls projecting laterally from the sides thereof to provide longitudinal rows of ice block compartments, the vertically disposed walls of one set of said laterally projecting walls being parallel to one another and extending in one direction transverse of the grid at an acute angle relative to said longitudinal wall, the vertically disposed walls of the other set of said laterally projecting walls
- 30 being parallel to one another and extending in another direction transverse of the grid at an acute angle relative to said longitudinal wall, the normal acute angled disposition of said laterally projecting walls providing said ice block compartments with a parallelogram form, said vertically disposed laterally projecting walls of each set thereof being movable toward the same end of the grid out of their normal acute angled extension towards a right angled position relative to said upright longitudinal wall to break ice blocks loose from said grid walls and to enlarge said ice block compartments, and mechanism carried by said grid and arranged to impart force to each of said laterally projecting vertical walls
- 35 to cause said movement thereof.
5. In combination, a tray having a unitary grid structure removably disposed therein, said grid structure comprising an upright rigid wall extending longitudinally of the tray and having a plurality of rigid vertically disposed walls pro-

jecting laterally from each side thereof to divide the interior of the tray into longitudinal rows of ice block compartments, said laterally projecting vertically disposed walls extending transversely of the grid at an acute angle relative to said longitudinal wall to provide said ice block compartments with a parallelogram form, said vertically disposed laterally projecting grid walls being movable out of their normal acute angled extension towards a right angled position relative to said upright longitudinal wall, and a lever having a single direction of motion for elevating said grid structure together with ice blocks bonded thereto relative to the tray and for moving said vertically disposed movable laterally extending grid walls to break the bond between the ice blocks and the grid walls and to enlarge said ice block compartments.

6. In combination, a tray having a unitary grid structure removably disposed therein, said grid structure comprising an upright rigid wall extending longitudinally of the tray and having a plurality of rigid vertically disposed walls projecting laterally from each side thereof to divide the interior of the tray into longitudinal rows of ice block compartments, said laterally projecting vertically disposed walls extending transversely of the grid at an acute angle relative to said longitudinal wall to provide said ice block compartments with a parallelogram form, said vertically disposed laterally projecting grid walls being movable out of their normal acute angled extension towards a right angled position relative to said upright longitudinal wall, and a lever having a single direction of motion for elevating said grid structure together with ice blocks bonded thereto relative to the tray and for imparting force to the outer extremity of said vertically disposed movable laterally extending grid walls to cause said movement thereof for breaking ice blocks loose from the grid walls and for enlarging said ice block compartments.

7. A structure in accordance with claim 1 wherein the means for imparting force to said vertically disposed laterally projecting walls acts against said longitudinal wall.

8. A structure in accordance with claim 3 wherein the lever is pivotally mounted to said longitudinal wall.

9. A grid for disposition in an ice tray comprising, a longitudinal upright wall and a plurality of vertically disposed walls projecting laterally from said longitudinal wall in spaced apart relation along the length thereof to form a row of ice block compartments, said laterally projecting vertically disposed walls normally extending at an angle other than a right angle to said upright longitudinal wall to provide said ice block compartments with a parallelogram form in at least one direction of cross-section, said laterally projecting vertical walls being movable out of said normal angled extension towards a right angled position relative to said upright longitudinal wall to enlarge said ice block compartments, and a lever movable in a direction lengthwise of said grid for imparting force to said laterally projecting vertical walls to cause said movement thereof.
